UNITED STATES PATENT OFFICE.

HARRIS D. HINELINE, OF NEW YORK, N. Y., ASSIGNOR TO RADIO CORPORATION OF AMERICA, A CORPORATION OF DELAWARE.

TELEPHONE RECEIVER.

Application filed May 20, 1926. Serial No. 110,336.

My invention relates to telephone devices and particularly to loud speaking telephone receiver devices.

An object of my invention is to provide a telephone receiver device adapted to transformation of substantial powers of vibratory electrical energy into sound.

Another object of my invention is to provide a loud speaker device adapted to the translation of electrical energy into sound with the minimum distortion from natural resonant frequencies.

Another object of my invention is to provide a loud speaker device having a diaphragm and a diaphragm chamber having a minimum volumetric capacity.

Another object of my invention is to provide a loud speaker device having a diaphragm and means for causing a minimum amount of steady flux to traverse the diaphragm.

In the prior art of the construction of telephone receivers difficulty has been encountered from the presence of the steady polarizing flux traversing the diaphragm because of saturation of the diaphragm, causing a doubling of the frequency and improper response to the impressed current. Difficulty has also been encountered in the production of a diaphragm chamber having a sufficiently small volume to give satisfactory reproduction of very high frequencies.

My invention provides a telephone receiver device in which the steady flux passes through the diaphragm only transversely to the diaphragm surface. It further provides a conveniently small diaphragm chamber volume and provides easy and convenient assembly means for the construction of the device.

Other objects and structural details of my invention will be apparent from the following description when read in connection with the accompanying drawing, wherein:

Figure 1 is a view in vertical elevation of my invention and,

Figure 2 is a horizontal section of the embodiment.

Referring to the figures, I provide a tubular permanent magnet structure 1 having north and south poles as indicated. A base member 2 is also provided having an inner tubular portion 3, and an outer tubular portion 4. A coil bobbin is provided, which may consist of a bobbin cheek 5, pressed well down upon the tubular member 3 and an addi-

tional bobbin cheek 6, pressed upon the end of the tubular portion 3. The tubular portion 4 may conveniently be screwed upon a ring member 7, attached to, or integral with the base member 2. A winding 8 is placed within the bobbin upon the tubular portion 3. If the tubular portion 4 is threaded upon the portion 7 as indicated, the coil 8 may be wound directly upon the tube 3 between the bobbin cheeks 5 and 6, or alternatively, the tubular portion 4 may be made an integral part of the base member 2 and the coil 8 may then be wound upon a bobbin having a tubular core and fitted over the member 3. The bobbin cheek 6 is conveniently made dished as shown.

A top plate member 9 having a tubular portion 11 and a larger tubular portion 12 threaded upon a ring portion 14 is provided. A bobbin cheek 15, a coil 16 and a dished coil 17 are provided as before, a diaphragm 18 is positioned between the bobbin cheeks 6 and 17 and the whole assembly is clamped together by a coupling member 19. The top plate 9 is threaded on its periphery as indicated and a clamping ring 21 is provided to clamp the magnet 1 in the position shown. A nozzle member 22 is provided having an opening coaxially through the tubular member 11, and a horn member 23 preferably having a flare which follows an equation of logarithmic form is attached thereto.

The diameter of the opening through the member 11 may preferably be about 1/4 of an inch. The spacing at points A and B between the tubular members 3 and 11 and the diaphragm 18 may desirably be less than 1/16 of an inch and may be as small as 1/64 inch although a much greater distance is suggested in the Figure.

In the operation of my device a steady flux is provided by the magnet 1 which flows as indicated by the solid line arrows, divided at the point of attachment of the tubular member 12 to flow longitudinally through the members 11 and 12. A portion of the flux crosses the spaces A and B through the diaphragm 18 as indicated and another portion flows adjacent the coupling 19, through the edges of the bobbin cheeks 6 and 17 as indicated. Thus only an annular ring at the extreme periphery of the diaphragm 18 and an annular ring near the center carry the steady permanent flux, and this flux is right angles to the plane of the diaphragm.

The coils 8 and 16 are wound in such a way as to oppose each other and they accordingly produce fields which change the flux of the permanent magnet N, causing a portion of it to flow in the path indicated by the dotted arrows thereby causing the diaphragm to be attracted to one or the other of the tubular pole members 3, according to the direction of current flow. The magnitude of the flux diverted from the straight path to a path through the diaphragm 18 is thus dependent upon the magnitude of current flowing in the coils 8 and 16, and varies with variations in the current, thus causing a varying pull upon the diaphragm 18, a movement thereof, and the production of sound vibrations thereby.

The horn 23 may desirably have an overall length of 5 ft. and a terminal opening not less than 12 or 14 inches in diameter. When so constructed practically uniform response in the production of sound is obtained from electrical frequencies ranging from about 100 per second to about 12,000 per second, the lower value being determined by the length and terminal opening of the horn 22 and the upper value being determined by the volume of the sound chamber surrounding the diaphragm 18, and the elasticity of the diaphragm.

The construction, as indicated, permits the utilization of a sound chamber over the diaphragm 18 having an extremely small volume, and the removal of all of the steady flux from the diaphragm permits the utilization of an extremely thin, light, elastic, diaphragm, thereby enabling the device to respond to very high frequencies. Simultaneously the use of the large logarithmic shaped horn loads the diaphragm sufficiently well so that it responds equally well to low frequencies.

The device may desirably be supplied with vibratory current through a transformer, in order to remove the direct current component when the device is connected to a vacuum tube amplifier. This prevents the existence of a steady flux through the diaphragm 18 due to the steady component of the vacuum tube amplifier plate current.

By the device of my invention I am enabled to provide a telephone receiver device which is capable of translating large powers of vibratory energy without distortion thereof and which is convenient to build and assemble and when constructed is rugged and durable.

While I have shown but one embodiment of my invention in the foregoing drawing and description it is capable of various modifications therefrom without departing from the spirit thereof, and it is desired therefore that only such limitations shall be imposed thereon as are required by the prior art or indicated by the appended claims.

I claim as my invention:

1. A telephone receiver device comprising a diaphragm, a magnet, pairs of coaxial pole

pieces of unlike polarity attached thereto on opposite sides of said diaphragm, adapted to carry magnetic flux transversely to said diaphragm and means for providing vibratory parallel flux in said diaphragm.

2. A telephone receiver device comprising a diaphragm, members forming a chamber therearound, a permanent magnet, a pair of concentric tubular pole pieces disposed on opposite sides of said diaphragm and connected to said magnet, a second pair of concentric tubular pole pieces disposed within said first named pair on opposite sides of said diaphragm and connected to said magnet, and a pair of concentric windings mounted on one of said pairs of pole pieces.

3. A telephone receiver device comprising a permanent magnet, a diaphragm, a pair of concentric pole pieces of like polarity on each side of said diaphragm attached to said magnet, and a winding mounted on one pole piece of each of said pairs of concentric pole pieces.

4. A telephone receiver device comprising a tubular permanent magnet having a plurality of concentric cylindrical poles at the opposite ends thereof connected thereto, a diaphragm mounted between said poles, and a pair of windings mounted on two of said cylindrical poles.

5. A telephone receiver device comprising a tubular permanent magnet having poles at the extremities thereof, a diaphragm of a less diameter mounted in said magnet transversely thereof, pairs of concentric tubular pole pieces connected to said magnet, and disposed on opposite sides of said diaphragm, and a winding on one of said poles.

6. In a telephone receiver device, a tubular magnet, a plurality of tubular coaxial pole pieces in said magnet connected thereto, windings mounted on two of said pole pieces, and a diaphragm associated with said pole pieces.

7. A telephone receiver device comprising a tubular permanent magnet, a circular diaphragm of less diameter positioned transversely therein, a plurality of symmetrical pole pieces cooperating with said diaphragm and said permanent magnet and coaxial therewith, and coils wound in opposition on two of said pole pieces.

8. A telephone receiver device comprising a tubular permanent magnet, a circular diaphragm mounted therein coaxial therewith, a plurality of tubular pole pieces cooperating with said magnet and coaxial with said permanent magnet and a winding mounted on one of said pole pieces.

9. A telephone receiver device comprising a tubular permanent magnet, a circular diaphragm transversely therein, a plurality of pole pieces cooperating therewith and attached to said magnet, adapted to convey flux therefrom through parallel concentric paths, and means comprising a winding for divert-

- ing part of said flux from one pole piece to another in a path parallel to the plane of said diaphragm.
10. In a telephone receiver device a dia-
phragm and a diaphragm chamber comprising
5 disks of insulating material adapted to
serve as bobbin cheeks.
11. In a telephone receiver device a dia-
phragm and a plurality of pairs of concen-
tric pole pieces of equal length and bobbin
10 cheeks cooperating therewith surrounding
certain of said pole pieces and supported be-
tween other of said pole pieces.
12. In a telephone receiver device a coni-
cal diaphragm chamber of minimum volume
15 comprising a conical bobbin cheek of insu-
lating material and a tubular pole piece.
13. In a telephone receiver device, a dia-
phragm, and a disk having a concave surface
20 mounted on each side thereof the concave
surfaces of said disks being opposed to form
a chamber for said diaphragm.
14. In a telephone receiver device, a dia-
phragm, pairs of pole pieces on opposite sides
thereof, and a diaphragm chamber comprising
25 disks mounted on one of said pairs of pole
pieces, and clamped between another of said
pairs of pole pieces.
15. In a telephone receiver device, a mag-
net, pairs of pole pieces therein connected
thereto, a diaphragm, and a pair of disks
30 forming a chamber for said diaphragm
clamped between a pair of said pole pieces.
16. In a telephone receiver device, a mag-
net, pairs of tubular pole pieces attached
thereto, and a diaphragm between said pairs
35 of pole pieces and supported by a pair of said
pole pieces.
17. In a telephone receiver device, a pair
of tubular pole pieces, and a metallic dia-
phragm clamped between said pole pieces
40 but insulated therefrom.

HARRIS D. HINELINE.
